UNITED STATES PATENT OFFICE.

CHARLES R. PRATT, OF NEW YORK, N. Y.

ELEVATOR.

SPECIFICATION forming part of Letters Patent No. 450,252, dated April 14, 1891.

Application filed September 10, 1890. Serial No. 364,533. (No model.)

To all whom it may concern:

Be it known that I, CHARLES R. PRATT, a citizen of the United States, residing at New York, county and State of New York, have 5 invented a certain new and useful Improvement in Elevators, of which the following is a specification.

My invention relates to elevators, and especially to that class known as "screw elevators"—that is, elevators in which a screw is turned by a suitable motor and a nut traveling on said screw moves a carriage or frame supporting suitable sheaves for the cable which supports the elevator.

15 The object of my present improvement is to economize in space required for the traveling carriage and other mechanism, to simplify the construction of the carriage, to reduce friction and wear between the several parts, and 20 to cheaply and efficiently steady or guide the carriage.

The invention consists in an improved carriage for said sheaves, in an improved arrangement of the sheaves, and in certain combinations hereinafter described and claimed.

25 In the accompanying drawings, which illustrate my invention, Figure 1 shows an end view of the carriage, the sheaves on one side of the carriage being in elevation and the 30 sheaves on the other side of the carriage being in section. Fig. 2 is a side view of a section of the screw and track with the carriage and nut in place thereon, the sheaves being omitted on the side of the carriage nearest to the observer. Fig. 3 is a section of the carriage-body on line X X of Fig. 2.

35 The screw 1 is mounted in suitable bearings wherein it may turn, but which prevent longitudinal motion, and to this screw power 40 is transmitted in any suitable way from an electric or other motor. Upon said screw is a nut 2, which is moved along by rotation of the screw, and which as it travels moves the carriage carrying the sheaves. Said carriage 45 slides along a track or way, preferably consisting of a heavy plank 3, of about four inches in width, mounted on an iron beam 4. Above the carriage two planks 5 are placed, one on either side of a beam 6. To strengthen this 50 guide in a transverse direction, a channel-iron or other shaped plate 7 is placed in the position indicated in the drawings. The body of

the carriage preferably consists of a single steel forging 8', having on each side a projecting trunnion 8, of sufficient length to receive the desired number of sheaves. To the lower side of said body is bolted or otherwise secured a projecting piece or guide 9, which is shaped to conform to the plank 3, and which is adapted to slide along the same. To the upper side of the body is secured a similar extension 10, which embraces the guide above described.

Onto each trunnion 8 is slipped a chilled-iron or other sleeve 11, and over this sleeve 65 rings 12, alternating with rows of steel balls 13, and over each row of balls a metal ring 14, the number of rings being the same as the number of sheaves to be employed. In the drawings five such sheaves 15 are shown. 70 When these have been put in place, the disk 16 is placed over the end of the trunnion and secured by means of suitable screws or other devices.

The rope or cable ordinarily employed in 75 elevators of this character is about five-eighths of an inch in diameter. When I use ropes of this size, I make the sheaves one-eighth of an inch thicker, and place them on the trunnion side by side, so that they bear against each 80 other through a portion at least of their surfaces, and especially at the hub and at the rim. With this construction and arrangement when the ropes are placed on the sheaves in the usual manner there will be 85 only one-eighth inch distance between any two adjoining lengths of the rope. The sheaves, being of considerable diameter, would require lateral support were it not for the fact that by the arrangement described the several 90 sheaves brace and support each other. In the operation of this device the several sheaves will turn in the same direction, but at slightly different speeds, as is well understood by those familiar with this character of devices. This 95 being so, the friction between the contiguous surfaces of the sheaves will not be great. In view of the narrow bearing-surface which each sheave has on the trunnion, there is a strong tendency to wear the bearing-surface; 100 but this is obviated by the arrangement of the friction-balls described.

By comparing the present apparatus with that shown and described in Patent No.

417,087, dated December 10, 1889, and that shown in my application, Serial No. 349,473, filed April 25, 1890, it will be apparent that a very material saving has been made in the floor-space occupied by the apparatus, in the number of parts employed in making the same, as well as a gain in general efficiency and durability of the apparatus, since the width of the carriage and track is reduced fully one-half and the cumbersome frame supporting the sheaves is dispensed with.

It is evident that the guides and certain other parts of the construction may be varied in form without departing from my invention.

15 Having thus described the invention, what I claim is—

1. The combination, in an elevator-hoisting apparatus, of a traveling carriage having trunnions and several sheaves mounted thereon, the surfaces of said sheaves being in contact, a guide on the carriage between the trunnions, and a track directly under the carriage, substantially as described.

2. The combination of an elevator-screw, a nut thereon and moved thereby, a carriage moved by said screw and nut, and several sheaves for the elevator-rope mounted on trunnions on both sides of said carriage, the sheaves on each side being side by side and 30 in contact with each other at or near their periphery, substantially as described.

3. The combination of an elevator-screw, a nut thereon, a carriage consisting of a body of metal with projecting trunnions, several

sheaves on said trunnions with faces in direct contact, and guides on said body between the sheaves and shaped to move on a suitable central track, substantially as described.

4. The combination, in an elevator-hoisting apparatus, of a traveling carriage having a body and trunnions consisting of a single piece of metal, several sheaves on said trunnions, and a track under the carriage, being narrower than the carriage and occupying the space between the sheaves, substantially as described.

5. The combination, in an elevator apparatus, of a track or way, a carriage movable along said way, cable-sheaves supported by the carriage on each side of the track, and a guide above the carriage for staying the same, substantially as described.

6. In an elevator-hoisting apparatus, the combination of a carriage movable along a way or track and consisting of a body and projecting trunnions, and cable-sheaves on said trunnions in surface contact with each other and separated from the trunnions by ball-bearings, there being an independent row of balls for each sheave, substantially as described.

This specification signed and witnessed this 2d day of September, 1890.

CHAS. R. PRATT.
